Patented Aug. 15, 1922.

Inventor:
Vandiver J. Van Horn

By Jonee Bain Winkle *fittp.*

UNITED STATES PATENT OFFICE.

VANDIVER J. VAN HORN, OF CHICAGO, ILLINOIS.

WRENCH.

1,425,816.

Specification of Letters Patent. Patented Aug. 15, 1922.

Application filed January 6, 1921. Serial No. 435,368.

To all whom it may concern:

Be it known that I, VANDIVER J. VAN HORN, a citizen of the United States, residing at Chicago, in the county of Cook and

5 State of Illinois, have invented certain new and useful Improvements in Wrenches, of which the following is a specification.

The invention relates to improvements in wrenches, and has particular reference to 10 ratchet wrenches.

One of the objects of the invention is to provide a durable, effective wrench.

Another object is to provide a wrench of few parts, designed for cheap construction.

15 Another object is to provide a reversible socket wrench.

Another object is to provide a wrench, the working parts of which are housed within 20 a single casing.

Another object is to provide a ratchet wrench in which the operating handle serves also as a positively operable pawl to move the ratchet rotatable member.

25 Another object is to provide a wrench particularly adapted for use on bolts positioned in narrow contracted areas.

Another object is to provide a ratchet wrench which is reversible by simply turning 30 the wrench over.

Other, further and more particular objects of the invention will become readily apparent to persons skilled in the art, from a consideration of the following description, 35 when taken in conjunction with the drawings, wherein:

Fig. 1 shows a plan view of the wrench.

Fig. 2 is a section taken on line 2—2 of Fig. 3, and

40 Fig. 3 is a section taken on line 3—3 of Fig. 2.

In all the views the same reference characters are employed to indicate similar parts.

45 In the drawings 5 represents a one-piece flat housing or casing providing substantially duplicate attached parts 6 and 7 connected together through the section 8 and closed at the angularly disposed arcuate contacting edges 9, the parts 6 and 7 are sufficiently separated to provide a space for the insertion of a handle 10. The parts 6 and 7 are perforated as at 11 and 12, respectively, which perforations are in perfect

50 55 register for enclosing the ratchet wheel 13 and substantially concentric with the outer

arcuate end of the housing. The wheel 13 is provided with lateral hubs 14 and 15, which substantially fit the openings 11 and 12 and with intervening ratchet teeth 16. 60 The wheel also has an angular opening 17 extending through the hubs for engaging a socket nut, bolt or the like.

A rivet 18 holds the members 6 and 7 together after the wheel 13 and the handle 10 65 have been placed therein. The handle is pivoted by a rivet 19 which passes through the members 6 and 7. The end of the handle is cut away in an oblique plane 20 and provides a toe 21 that engages the teeth 16 of 70 the wheel 13. The handle also has a notch 22 in which is inserted an open spiral spring 23 which holds the toe 21 normally in contact with the wheel.

Look at Fig. 2 and assume that there is a 75 member in the opening 17 to be turned by the wrench: pushing on the handle 10 until it is brought into dotted line position, the handle and housing are moved in that direction, while the wheel 13 remains stationary. 80 The spring 22 is overcome by the effect of pressure exerted upon the handle so that the toe 21 of the handle clears the teeth 17, as clearly shown in dotted lines as at 24. Now, when the handle is brought back to 85 full line position the wheel 13 will have been rotated the distance of one tooth. If it is desired to rotate the member that is located in the opening 17, in the opposite direction, by use of the wrench, it is only 90 necessary to reverse the wrench; that is, to turn it upside down, whereupon the operation I have described will forcibly rotate the wheel 13 in anti-clockwise direction.

The housing 5 is contracted, at 25, to a 95 width that will just admit the handle 10, so as to permit the teeth of the wheel 13 to be the same width as the handle. The hubs 14 and 15 of the wheel are laterally beyond the wheel in contact with the surfaces 100 bounding the openings 7 and 12. The thin flat construction and rounded ratchet end of the wrench adapts it especially for use on bolts positioned in narrow contracted portions of a structure which are inaccessible 105 to the ordinary wrench.

Having described my invention what I claim as new and desire to secure by Letters Patent, is:

1. A wrench having a one-piece housing 110 provided with flat, perforated, folded housing members, each having bounding walls

angularly related to the flat members and placed edge to edge; a ratchet wheel having lateral shoulders, smaller in diameter than the teeth of the wheel, one on each side thereof journaled in the respective openings; a handle, pivoted in said housing, having a toe engaging said teeth and a notch in its edge, near the toe and an open coiled spring in said notch, having one end in contact with the handle and the other in contact with the side wall of the housing.

2. A wrench comprising a flat housing having one end rounded and having registering side openings, said side openings

being near the rounded end and substantially concentric therewith; a ratchet wheel mounted in the housing with its hubs journaled in the openings, said wheel having an angular opening extending longitudinally through the hub; a handle pivoted in the housing and having a pawl shaped end engaging the teeth of the ratchet wheel; and a spring mounted in the housing that yieldingly holds the pawl shaped end of the handle in contact with the ratchet wheel.

In testimony whereof I hereunto subscribe my name:

VANDIVER J. VAN HORN.
